UNITED STATES PATENT OFFICE.

JOHANN BASCHKIN, OF KOLOMNA, MOSCOW, RUSSIA.

INJECTOR

1,038,826.

Specification of Letters Patent. Patented Sept. 17, 1912.

Application filed February 21, 1912. Serial No. 679,086.

To all whom it may concern:

Be it known that I, JOHANN BASCHKIN, a citizen of the Russian Empire, residing at Kolomna, Government of Moscow, Russia, 5 have invented certain new and useful Improvements in Injectors, of which the following is a specification.

The present invention relates to improvements in injectors and has the object to 10 improve the working of such injectors by a peculiar construction and arrangement of the parts and to facilitate the assembling of the various parts of which the injector is composed.

15 The invention further relates to an injector in which after it has been started an additional conveyance of water can be effected by the overflow or slobbering tube without any valves or the like having to be 20 operated, without the water and hot steam being lost, which are discharged from the mixing chamber during the starting period.

The invention lastly relates to the arrangement of certain hose connections when 25 injectors are employed in pairs, by which arrangement the number of necessary hose connections is reduced and the freezing of the one injector is avoided, when it might have become defective and only one of the 30 injectors can be kept working.

For obtaining these objects the present invention provides that the insides of the condensation or mixing nozzle at the point of inlet for the water and at both sides of 35 the first overflow, and the opposite outsides of the suction nozzle and the steam nozzle are made of a cylindrical shape. Also the inside of the suction nozzle at its narrowest part and the opposite outside of the steam 40 nozzle are of a cylindrical shape. From this arrangement it results that at the narrowest part of the annular passage formed between the suction and the steam nozzles for the suction steam, and at the 45 inlet for the water at the condensation nozzle and the bore of the condensation nozzle inclosing the first overflow, sectional areas of constantly equal area are maintained, without detriment of small inaccuracies in the 50 assembling.

To insure a proper working of an injector it is necessary that the above mentioned parts shall be of exactly the proper size. Especially the two annular channels located 55 on both sides of the first overflow and

formed by the parts of the two bores of the mixing nozzle and of the opposite outside of the steam nozzle must be of absolutely the same area. It is extremely difficult to obtain this with the conical nozzles hitherto 60 usually employed as the least inaccuracy in assembling, that is to say, if the one nozzle is pushed too far or too little into the other will change the dimensions of these 65 passages. A change in the dimensions of these 70 passages will, however, unfavorably affect the efficiency of the injector and increase the loss of water. This explains the frequently observed fact that injectors of the type hitherto used show, according to the 75 wear of the nozzles, in consequence of the increasing irregularity of the passage apertures at both sides of the first overflow an increasing loss of water. Even if the nozzles are accurately made after gages and 80 are properly assembled it will sometimes happen, that the injector must be readjusted when tested, which will of course considerably increase the cost of manufacture.

The object of the present invention is to 85 obviate these existing troubles so as to simplify the repairing of injectors on the one hand, and on the other to reduce their manufacturing cost, and lastly to render them less sensitive against wear of the nozzles. 85

A further improvement in the construction of injectors consists according to the present invention in that the steam passages, which form the communication between the suction nozzle and the steam 90 chamber enter into the conical seating surface of the cone closing the steam nozzle between the seat proper of the cone and the bore of the steam nozzle, whereas hitherto these passages were arranged at the bottom 95 of the cylindrical enlargement of the central nozzle. In consequence of the new arrangement much less steam than hitherto will flow into the suction nozzle when the central or steam nozzle is completely opened, so that 100 the sucked up water will be less highly heated than it is the case in injectors, the suction steam passages of which are arranged in the aforementioned manner.

105 Preferably these improvements in the nozzles according to the present invention are embodied in such apparatus, in which the mixing or overflow chamber may, after the injector has been started, be used for an additional conveyance of water. For this pur- 110

pose the suction chamber and the mixing chamber are preferably made in injectors of this type to communicate with the water tank by means of two tubes reaching into the water, these tubes being either entirely valveless or having valves of such a type that a continuous unobstructed passage from the suction or mixing chamber respectively to those ends of the two tubes which are located toward the water tank can be produced. The tube communicating with the mixing or overflow chamber will hereinafter be termed the "supplementary tube," as it is employed to supplement the conveyance of water after the injector has been started. This supplementary tube may during the starting period of the injector act as an overflow tube and guide the water, the steam, and the air emerging from the overflow chamber into the water tank.

When the injector has been started, the direction of the flow of the water in the supplementary tube is reversed, so that no water will be forced from the mixing chamber into the water tank, but on the contrary water will be sucked from the water tank into the mixing room. Thus the supplementary tube can serve as a substitute for the customary slobbering valve, whereby the efficiency of the injector is increased by the two tubes sucking up the water, whereby the reliability is increased by no intermediate valves subject to wear being necessary, and whereby finally the loss of water by the mixing valves is reduced. Such injectors may be arranged in pairs and for insuring a greater simplicity the pipes leading to the water tank may be joined in pairs as shall be hereinafter described.

In the accompanying drawings Figure 1 is a longitudinal section through the preferred embodiment of the invention, Fig. 2 is a longitudinal section through an injector according to Fig. 1, in which the suction and the mixing chambers communicate by means of two independent pipes with the water tank, and in which the mixing overflow chamber is provided with a mixing or overflow valve, which may be operated only when the supplementary tube communicating with the mixing chamber is or has been shut off. Fig. 3 is an embodiment according to Fig. 2 in which the mixing valve is arranged in a valve chamber laterally projecting from the supplementary pipe and can be made to communicate with the mixing chamber by means of a three way cock. Fig. 4 is a plan view of two injectors, each of which communicates with its separate suction pipe, whereas the two supplementary pipes join to one common pipe. Fig. 5 is a plan view of two injectors, the supplementary pipe of the one injector being connected with the suction pipe of the other injector.

In the drawings 1 is the body or cas-

ing of the injector, which is provided in the usual manner with a connection 2 for the steam supply, a connection 3 for the water supply, and an overflow or slobbering aperture 4, through which the water entering into the mixing chamber 5 can escape. The injector has besides, as customary, a mixing or condensation nozzle 6, a pressure nozzle 7, a connection piece 3 for the water delivery pipe, a feed valve 9, a central or steam nozzle 10, and a starting nozzle 11. The condensation nozzle 6 and the pressure or delivery nozzle 7 are as usual connected with each other on their narrowest part by means of a connection piece 12, which contains overflow openings 13, through which the surplus water can escape.

The condensation nozzle 6 is conically flared toward the water chamber 14 and has at its narrowest part the customary overflow openings 15, through which the surplus water can pass into the mixing chamber 5 when the injector is started. The two sections 16 and 17 of the bore of the condensation nozzle at the two sides of these overflow openings 15 are of a cylindrical shape; likewise the rear part 18 of the bore leading into the water chamber 14 is cylindrically shaped.

The suction or starting nozzle 11 is carried by the cylindrical head 19 of the steam nozzle 10. On its outside opposite the inlet 18 for the water of the condensation nozzle it is of a cylindrical shape and has a bore which is conically enlarged toward both sides. The two conical ends of the bore communicate by means of a cylindrical part 20. The outside of the steam nozzle 10 opposite to this part 20, and the outside of this steam nozzle 10 opposite to the cylindrical parts 16 and 17 of the bore of the condensation nozzle are made of a cylindrical shape. Thus considerable independence of the accuracy with which the assembling is carried out is obtained, as the area of the passages formed by the said parts for the steam and the water respectively will remain the same even if the assembling should not be so accurately carried out, which is not the case with injectors of the hitherto customary kind, which employ conical nozzles only.

The bore 21 of the steam nozzle 10 is closed by a conical plug 22 coöperating with a conical bore 23 in the cylindrical part 19 of the steam nozzle. Behind the seat of the cone 22 are arranged steam passages 24 through which steam can pass from the steam chamber 25 into the annular passage formed by the outside of the steam nozzle 10 and the bore of the starting nozzle 11, when the cone 22 is lifted. The cone 22 is carried by the end of a rectilinearly guided rod 26 and may in the embodiments represented in the drawings be forced against or lifted

from its seat by means of a hand lever 27. The rod 26 is passed through a stuffing box 28 of any known or suitable type.

For starting the injector the cone 22 is slightly lifted from its seat by means of lever 27. The steam will then pass from the steam chamber 25 through the passages 24 to the starting nozzle 11 and will thereby suck in the known manner water from the water pipe connected at 3, the surplus water passing through the overflow openings 15 into the mixing or overflow chamber. After the injector has been started the cone 22 is completely lifted, so that the steam will pass through the steam nozzle 21. The operation is then the same as usual. In consequence of the peculiar arrangement of the steam passages forming the communication between the steam chamber and the starting nozzle 11 only very little steam can pass through the passages 24 into the sucked up water and heat the latter, when the cone 22 is completely lifted from its seat. By all means the amount of steam entering, which may have a detrimental effect on the efficiency of the injector is smaller, than if the passages 24 opened as hitherto customary in the front end of the cylinder head 19 into the steam chamber 25, as in this case steam can enter unpreventedly as before from the steam chamber. By the steam passages 24 however opening into the conical seat of the cone 22 much less steam will enter into the starting nozzle, as the steam supplied will chiefly pass through the bore 21 of the steam nozzle which offers a smaller resistance than the bores 24.

In the embodiments according to Figs. 2 to 5 two independent pipes 29, 30 are connected to the suction connection 3 and the overflow connection 4; of these pipes 29, 30 the former may be called the "suction pipe," the other the "supplementary pipe." The pipes 29, 30 may be shut off from the suction chamber 14 or the mixing chamber 5 by cocks 31, 32 each of which has a bore 33, which is normally in the position shown in Figs. 2 and 3, in which they provide for a free communication between the suction and the mixing chamber respectively and the water tank 34. In the embodiment according to Fig. 3 the cock 32 of the supplementary pipe 30 is provided for reasons given hereinafter with a side passage 35, so that the pipe 30 is shut off from the mixing or overflow chamber 5 by means of a three-way cock.

In the embodiment according to Fig. 2 a mixing valve 36 is arranged on the mixing chamber 5, which valve is under the action of a screw operated by means of a handle 37 and by means of which the valve may either be tightly pressed against the seat or be allowed to rise from its seat so as to allow the escape of air, water, steam or the

like. The valve 36 is guided by a guide 39 and may if desirable be under the influence of a spring which tends to keep it permanently pressed against its seat. Laterally projecting from the valve casing 40 is an outlet 41, through which, if necessary, water, air, steam and the like may be discharged.

In the embodiment according to Fig. 3 plate 42 is substituted for the valve casing 40, by means of which plate access may be had to the overflow chamber so that this chamber may be inspected. To the supplementary pipe 30 a valve 42 is connected opposite to the three-way cock 32, in which valve casing a valve 45 moves in a guide 44, and is held pressed against its seat by the action of a spring 46. The valve controls the communication between a passage 47 at the one side and an outlet 48. According to the position of the cock 32 this valve at the side is entirely shut off or it is in communication with the mixing chamber 5 through the side passage 35 after the supplementary pipe 30 has been shut off so that the valve 45 can be used like an ordinary slobbering valve.

The operation of the injectors shown in Figs. 2 and 3 is as follows: Normally the screw 38 is, in the embodiment according to Fig. 2, in its depressed position, so that the valve 36 is positively held against its seat, and the cocks 31 and 32 are in the positions shown in Figs. 2 and 3, in which there exists a clear communication between the suction chamber or the mixing chamber and the suction pipe or the mixing pipe respectively, while the slobbering valves are completely tripped out of action. In this case the injector operates as follows: At the commencement of the work, viz., in starting the water escaping from the overflows 15 or 13, the not condensed steam and the like pass through the vertical opening 33 in the cock 32 and the supplementary pipe 30 into the water tank 34. Consequently no slobbering or overflow valve is required and the water and steam escaping from the overflow chamber are not lost, as they are carried into the water tank, where they will cool down or be condensed respectively. When the injector is at full work, that is when there exists a vacuum in the mixing chamber, the direction of the flow in the supplementary pipe is simply reversed, and water will now flow from the tank 34 through the supplementary pipe 30 into the mixing chamber 5 and thence into the overflows and the delivery pipe 8. The supplementary pipe will thus act as an automatic regulating member, which on the pressure period in the mixing chamber having changed to the vacuum period, will automatically control the supplementary conveyance of water through the mixing chamber, which supplementary conveyance is by itself known, but only by

means of mechanically operated valves. If for some reason or other an additional conveyance of water through the supplementary pipe cannot or shall not occur, the supplementary pipe 30 is shut off from the tank 34 by the cock 32 and the mixing valve 36 or 45 respectively according to Figs. 2 and 3 is turned on. For the purpose the screw 38 is screwed up in the casing 40 by means of the handle 37, so that the valve 36 can play freely. In the embodiment according to Fig. 3 the valve 32 is in the above mentioned case adjusted in such a manner, that the lateral passage 35 comes into alignment with the passage 47, so that the pipe 30 is shut off and the valve 45 can act as mixing valve. In this case the injectors shown in Figs. 2 and 3 act as ordinary injectors, and water is conveyed through the suction pipe 29 only while the pipe 30 remains idle and the mixing valves act in the usual manner allowing hot water, steam, air and the like to escape when the injector is started while as soon as a vacuum appears in the mixing chamber they will settle down on their seats and close the mixing chamber against the outer atmosphere.

In Fig. 4 is shown a plan view of two injectors, which are to be employed simultaneously, say on a locomotive or the like. These injectors have the nozzles constructed as shown and described with regard to Fig. 1, and the special constructional form according to Fig. 2. Of course also injectors according to Fig. 3 or injectors in which no safety overflow valve at all is provided may be used. The two supplementary pipes 30 are joined to one common pipe 49, while the pipes 29 are left separate, so that only three hose connections lead from the two injectors to the water tank.

In the embodiment according to Fig. 5 the suction pipe 29 of the one injector communicates with the supplementary pipe 30 of the other injector, so that both injectors communicate by two pipes 50 only with the water tank. In consequence of these hose connections the number of hose between the locomotive and the tender can be considerably reduced. Besides the hose connection according to Fig. 5 avoids that the one injector can freeze, in case for some reason or the other only one injector is working and the two do not alternate. For if the one injector is started, the hot surplus water will flow from the mixing chamber of the one injector through its supplementary pipe into the water pipe of the other injector and heat the latter so that its hose cannot freeze. If the other, say the left, injector is already working, it will suck the water through both its pipes, that is from its left pipe and the pipe of the injector on the right. If the injectors have not such a pipe connection, the aforescribed movement of the water is

not produced, so that the idle injector may freeze.

As is evident from the drawings the two injectors are not independent when the pipe connections are as shown in Fig. 4. If therefore for some reason the one hose between engine and tender, say the left one, should become defective, that is, to say, burst or become choked, both injectors will stop working. If in this case the defective supplementary pipe is cut off from the injector on the right, and the mixing valve is turned on, the injector on the right will work like an ordinary injector, independently of the other injector on the left.

The necessity of employing the mixing valves will also be observed, if with the pipe connections according to Fig. 5 the one injector, say the right one is to be started, while the other, the left one is already working. In this case the hot water, which flows through the right supplementary pipe into the left suction pipe may cause the left injector to refuse. For avoiding this it is only necessary to shut off the supplementary pipe of the right injector on starting the latter and to turn on the mixing valve. After starting, when the right injector is fully at work, the supplementary pipe can be turned on again, whereupon both injectors will continue working uninterruptedly.

What I claim is:

1. In an injector, a casing, a steam inlet, a water inlet, an overflow chamber, an overflow outlet and a water outlet in the said casing, a pressure nozzle located within the said overflow chamber and adapted to communicate with the said water outlet, a mixing nozzle communicating with the said water inlet and connected to the said pressure nozzle, overflow apertures between the mixing nozzle and the pressure nozzle, a steam nozzle, having a cylindrical end portion, adapted to communicate with the steam inlet and projecting into the said mixing nozzle, and means for controlling the admission of steam from the said steam chamber to the said steam nozzle, said mixing nozzle having a cylindrical bore opposite to the said cylindrical portion of the said steam nozzle.

2. In an injector, a casing, a steam inlet, a water inlet, an overflow chamber, an overflow outlet and a water outlet in the said casing, a pressure nozzle located within the said overflow chamber and adapted to communicate with the said water outlet, a mixing nozzle, being provided with a cylindrical bore at its inlet end, communicating with the said water inlet and connected to the said pressure nozzle, overflow apertures between the mixing nozzle and the pressure nozzle, a steam nozzle adapted to communicate with the said steam inlet and projecting

into the said mixing nozzle, a starting nozzle, having a cylindrical outside on its end adjacent to the said mixing nozzle, surrounding the said steam nozzle, and adapted to communicate with the said steam inlet, and means for controlling the admission of steam to the said steam nozzle and to the said starting nozzle.

3. In an injector, a casing, a steam inlet, a water inlet, an overflow chamber, an overflow outlet and a water outlet in the said casing, a pressure nozzle, located within the said overflow chamber and adapted to communicate with the said water outlet, a mixing nozzle communicating with the said water inlet and connected to the said pressure nozzle, overflow apertures between the mixing nozzle and the pressure nozzle, a steam nozzle adapted to communicate with the said steam inlet, projecting into the said mixing nozzle and having a cylindrical outside on that end projecting into the bore of the said mixing nozzle, said mixing nozzle having a cylindrical bore at the inlet end and on that part surrounding the cylindrical part of the said steam nozzle, a starting nozzle, having a cylindrical outside on its end adjacent to the said mixing nozzle, surrounding the said steam nozzle and adapted to communicate with the said steam inlet, and means for controlling the admission of steam from the said steam chamber to the said starting nozzle and to the said steam nozzle.

35 4. In an injector, a casing, a steam inlet, a water inlet, an overflow chamber, an overflow outlet and a water outlet in the said casing, a pressure nozzle located within the said overflow chamber and adapted to communicate with the said water outlet, a mixing nozzle, having a cylindrical bore at its inlet end, communicating with the said water inlet and connected to the said pressure nozzle, overflow apertures between the said mixing nozzle and the said pressure nozzle, a steam nozzle adapted to communicate with the said steam inlet and projecting into the said mixing nozzle, a starting nozzle surrounding the said steam nozzle, and having a cylindrical outside on that end adjacent to the said mixing nozzle and a partially cylindrical bore, and adapted to communicate with the said steam inlet, the said steam nozzle being provided with a cylindrical outside on that part surrounded by the cylindrical part of the bore of the said starting nozzle, and means for controlling the admission of steam from the said steam chamber to the said starting nozzle and to the said steam nozzle.

5. In an injector, a casing, a steam inlet, a water inlet, an overflow chamber, an overflow outlet and a water outlet in the said casing, a pressure nozzle located within the said overflow chamber and adapted to communicate with the said water outlet, a mixing nozzle communicating with the said water inlet and connected to the said pressure nozzle, overflow apertures between the said mixing nozzle and the said pressure nozzle, a steam nozzle adapted to communicate with the said steam inlet, a starting nozzle surrounding the said steam nozzle, and having a cylindrical outside on that part surrounding the cylindrical part of the bore of the said starting nozzle, and means for controlling the admission of steam from the said steam chamber to the said starting nozzle and to the said steam nozzle.

municate with the said water outlet, a mixing nozzle, having a cylindrical bore at its inlet end, communicating with the said water inlet and connected to the said pressure nozzle, overflow apertures between the said mixing nozzle and the said pressure nozzle, a steam nozzle, adapted to communicate with the said steam inlet, projecting into the said mixing nozzle and having a cylindrical outside between its ends and on that end projecting into the mixing nozzle, the said mixing nozzle having a cylindrical bore on that part surrounding the cylindrical outside of the said steam nozzle, a starting nozzle surrounding the said steam nozzle, adapted to communicate with the said steam inlet and having a cylindrical outside on the end adjacent to the inlet end of the said mixing nozzle, and a partially cylindrical bore around the cylindrical middle-portion of the said steam nozzle, and means for controlling the admission of steam from the said steam chamber to the said starting nozzle and to the said steam nozzle.

6. In an injector a casing, a steam inlet, a water inlet, an overflow chamber, an overflow outlet and a water outlet in the said casing, a pressure nozzle, located within the said overflow chamber and adapted to communicate with the said water outlet, a mixing nozzle, communicating with the said water inlet and connected with the said pressure nozzle, overflow apertures between the said mixing nozzle and the said pressure nozzle, a steam nozzle adapted to communicate with the said steam inlet and projecting into the said mixing nozzle, a head carrying the said steam nozzle, a starting nozzle carried by the said head and surrounding the said steam nozzle, controlling means for the admission of steam to the said steam nozzle and to the said starting nozzle comprising a cone controlling the admission of steam to the said starting nozzle, and a stud adapted to enter the bore of the said steam nozzle and controlling the admission of steam to the said steam nozzle and steam passages in the said head between the bore of the said starting nozzle and the said steam nozzle, and having their entrance opening behind the cone and in front of the stud controlled part of the bore of the said steam nozzle.

7. In an injector a casing, a steam inlet, a water inlet, an overflow chamber, an overflow outlet and a water outlet in the said casing, a pressure nozzle located within the said overflow chamber and adapted to communicate with the said water outlet, a mixing nozzle communicating with the said water inlet and connected to the said pressure nozzle, overflow apertures between the said mixing nozzle and the said pressure nozzle, a steam nozzle adapted to communicate with the said steam inlet, a starting nozzle surrounding the said steam nozzle, and having a cylindrical outside on that part surrounding the cylindrical part of the bore of the said starting nozzle, and means for controlling the admission of steam from the said steam chamber to the said starting nozzle and to the said steam nozzle.

cate with the said steam inlet and projecting into the said mixing nozzle, means for controlling the admission of steam to the said steam nozzle, a suction pipe connecting the water inlet to a water tank, a supplementary pipe, connecting the water tank to the overflow chamber and adapted to convey hot water or uncondensed steam to the water tank during the starting period and 10 to convey water through the said overflow chamber and the said overflow apertures to the said pressure nozzle after the injector having been started, manually-operated means for throwing the said supplementary 15 pipe into or out of action and an overflow valve adapted to be thrown into or out of action.

8. In an injector a casing, a steam inlet, a water inlet, an overflow chamber, an overflow outlet and a water outlet in the said casing, a pressure nozzle located within the said overflow chamber and adapted to communicate with the said water outlet, a mixing nozzle communicating with the said 20 water inlet, means connecting the said pressure nozzle to the said mixing nozzle, overflow apertures in the said connecting means connecting the said mixing nozzle and the said pressure nozzle to the said overflow 25 chamber, means for controlling the admission of steam from the said steam chamber to the said steam nozzle, a water tube connected to the said water inlet and adapted to convey water from a tank through the 30 said water inlet, the said mixing nozzle and the said pressure nozzle to the said water outlet, a supplementary tube connected to the said overflow chamber and adapted to discharge water from the overflow chamber 35 to the said water tank during the starting period of the injector and to convey water from the water tank through the said over- 40

flow apertures and the said connecting means to the said pressure nozzle after the injector having been started, a valve casing adapted 45 to communicate with the said supplementary tube, an overflow valve, located with the said valve casing and a three way cock in the said supplementary tube adapted to throw the said supplementary tube or the 50 said overflow valve into or out of action.

9. In an injector arrangement two injectors, each injector provided with an overflow chamber, an overflow valve and means for throwing the overflow valve into and 55 out of action, a water tank, water tubes connecting the water inlet of both injectors to the said water tank, supplementary tubes connecting the said water tank to the overflow chamber of the two injectors, the 60 supplementary tube of the one injector being connected to the supplementary tube of the other injector substantially as and for the purpose described.

10. In an injector arrangement two injectors, each injector provided with an overflow chamber, an overflow valve and means for throwing the overflow valve into and out of action, a water tank, water tubes connecting the water inlet of both injectors 70 to the said water tank, supplementary tubes connecting the said water tank to the overflow chamber of the two injectors, the water tube of either injector being connected to the supplementary tube of the other injector 75 substantially as and for the purpose described.

In testimony whereof I affix my signature in presence of two witnesses.

JOHANN BASCHKIN.
